UNITED STATES PATENT OFFICE.

JOHN WILLY, OF CHICAGO, ILLINOIS.

RECORD-SLIP SUPPORT.

1,380,877.

Specification of Letters Patent. Patented June 7, 1921.

Application filed July 16, 1919. Serial No. 311,134.

To all whom it may concern:

Be it known that I, JOHN WILLY, a citizen of the United States, residing at Chicago, in the county of Cook and State of Illinois, have invented a certain new and useful Improvement in Record-Slip Supports, of which the following is a specification.

My invention relates to an information rack such as may be used for hotel front offices, golf club handicapping devices, directories or anything of that kind where it is necessary to have a large number of small separate items which may from time to time be moved. One object is to provide such a rack wherein separate holders or carriers may be provided for each item and wherein an item or notation may be changed on the holders or carriers and the carrier thus may be easily and conveniently changed in position.

In general terms, my invention comprises the use of a flat slotted rack, a series of separate indicating blocks attached to the face 25 of the flat rack by means of rearwardly projecting key shaped members, so shaped that they will pass through the slots in the rack when the block is in substantial parallelism with the slot but will be held snugly in position when the block is perpendicular to the slot. A series of these blocks may be separated one from the other, all held from the rear by engagement with the slot. When it is desired to withdraw any one of them, all 30 that is necessary is to lift up all above the one to be withdrawn until sufficient room is had to turn it when it may be slipped out and placed anywhere desired. The slot must always be longer than the column of blocks by 40 a distance equal to the length of one of the blocks.

I propose to fasten information sheets or slips on the blocks by means of a rounded knob projecting through the end of the block 45 which knob will engage the perforation in the slip. This rounded perforation will have an inward cut which will give the necessary clearance to enable the round perforation to pass over the knob but will hold the slip 50 firmly on the knob in such wise that it will not be blown or fall off and cannot be inadvertently removed except by actually tearing the fabric of the slip itself.

My invention is illustrated in the accompanying drawings wherein—

Figure 1 is an elevation of my invention;

Fig. 2 is a vertical section on the line 2—2 of Fig. 1;

Fig. 3 is an elevation of one of the information slips;

Fig. 4 is a rear view of one of the blocks.

Like parts are indicated by like characters throughout.

A is the main supporting frame with a central slot A¹ which is enlarged at the rear 65 as at A².

B, B are sliding blocks, in each of which is positioned the screw threaded member B¹ enlarged and flattened as at B² for engagement with the slot A¹. B³, B³ are pins in the 70 front face of the block B adapted to support the information slip C which is perforated at C¹ C¹. C², C² are slits extending from the perforations C¹, C¹. C³ is a base rest adapted to support the row of blocks 75 from below.

The use and operation are as follows:—

There may be one or more separate columns of record blocks. Each of them will be held against the face of the rack by 80 the key engaging the slot and there will be enough clearance at the top of the rack so that the blocks in the column may be moved up to make it possible to rotate any one of the blocks far enough to let the key come out 85 through the slot. At other times all the blocks will be held by their engagement with the slot. By this arrangement any individual block may be moved about in the column or from one column to another without any particular difficulty.

In addition to this the separate information slips are detachably fastened upon the blocks and held there so that they cannot be blown or dropped off without complete destruction of the slip. The rounded pin or knob comes right down flush with the face of the block and so when the flat paper slip with its small round holes is put on the block, each one of these holes engages one of the knobs and tends to seek the smallest diameter of the knob. The result is that the slips of paper are held snugly against the face of the block by the engagement of the walls of the perforations with the knobs.

These perforations, in order to be sure that they are held snugly, ought to be just the size of the knob. This being the case, they are likely to tear or make too tight a fit with the knob. That difficulty is obviated 110 by providing the inwardly extending cuts or slots in the body of the paper. This en-

ables the perforations to expand sufficiently to make a smooth and working fit on the knob. At the same time, however, the paper is continuous outside the knob and a pull 5 on the paper between the two ends, will not be able to cause a release of the paper slip from its proper position. If the cut extended from the perforation out to the edge of the paper, as is ordinarily the case when 10 paper is perforated to engage a post or knob, clearly we would only have the resistance to bending of the paper to hold the strip in place, whereas, the scheme which is here proposed will have the actual tensile strength 15 of the paper serving to hold the slip in place.

My apparatus is peculiarly fitted for use in hotel offices and the like where different kinds of information must be available at all 20 times and wherein sudden and frequent changes in the entries are made. The idea is, for instance, that if you have a man in a room, you will write his name and the room number on a slip and stick that slip on one 25 of the record blocks. You will then put the slip in its numerical or alphabetical sequence in the rack. If now the man changes rooms, it is only necessary to change the room number on the slip and take out the block and 30 put it with the new number back in its numerical sequence, or re-arrange an alphabetical arrangement.

Then again in connection with handicapping schemes for golf clubs, each player has 35 a slip of paper with his name on it and he enters on that slip his scores. His handicap position depends on the scores. He can move his block about in the rack to its proper place, depending upon his score. He can 40 do this without detaching the slip from the block and if at some later date they no longer want to keep his score, all they have to do is to pull his slip off the block and the block is available for another score.

The main supporting board may be hung 45 vertically or laid down as, for example, upon a table. In order to locate the blocks in the board, they are turned so as to lie parallel to the slot and the broad portion of the wing screw is inserted within the slot. The block 50 is then turned so as to lie across the slot and may be moved about without disengagement therefrom. The information desired, such, for example, as names or numbers, is written upon the slips and slipped over the 55 pinheads on the block. This is, of course, interchangeable.

With my device arranged as above outlined, any rearrangement is simple. If I desire to remove one block or to change its 60 position with relation to the other, I merely raise them sufficiently to turn it parallel to the slot and remove it. In the same manner I then replace it at any desired point.

I claim—

1. The combination with a record slip of 65 a support therefor, comprising a plurality of face projections, a plurality of separate perforations in said slip to engage said projections, each of said perforations inwardly 70 slit toward and short of the other.

2. A record slip having a perforation in each end, there being a slit in the slip extending from each perforation toward and short of the other, a holder for record slips comprising a supporting member having a flat 75 slip engaging surface, and a plurality of rounded knobs projecting from and substantially tangent to said surface the slits being adapted to pass over said knobs.

In testimony whereof, I affix my signature in the presence of two witnesses this 12th day of July, 1919.

JOHN WILLY.
